UNITED STATES PATENT OFFICE.

ANDREW BOLTON, OF MANCHESTER, ENGLAND.

APPARATUS FOR SUPERHEATING STEAM.

SPECIFICATION forming part of Letters Patent No. 730,087, dated June 2, 1903.

Application filed January 27, 1903. Serial No. 140,705. (No model.)

To all whom it may concern:

Be it known that I, ANDREW BOLTON, a subject of the King of Great Britain and Ireland, residing at 49 Deansgate, Manchester, in the county of Lancaster, England, have invented new and useful Improvements in Apparatus for Superheating Steam, of which the following is a specification.

This invention relates to improvements in apparatus for superheating steam after leaving the boiler and before passing to the engine or other place where it is to be utilized, such as is described in the specification of the British Patent No. 19,466 of 1900.

15 The object of this my present invention is to obtain more effective superheating than is capable of being produced by superheaters of the downtake type hitherto constructed.

15 In the accompanying drawings, illustrating my invention and to which I hereinafter refer, Figure 1 is an elevation, and Fig. 2 a plan, (both partly in section,) of my improved apparatus and connections therewith. Fig. 3 is an end elevation of the same. Fig. 4 shows the same apparatus, drawn to an enlarged scale.

In the views the same letters refer to like parts.

According to my present invention I provide a box, as *b*, with superposed horizontal chambers *b'*, *b²*, and *b³*, the upper chambers *b²* and *b³* being each of similar dimensions and the lower chamber *b'* equal in length and breadth to the two upper chambers. I drill 35 small holes in the plate *b⁴*, which divides the lower from the upper chambers and form holes corresponding in number and position, but larger in diameter, in the bottom of the box. I pass tubes *d* and *d^x*, which are open at both 40 ends through the last-named holes in the bottom of the box and fit the upper ends of said tubes in the division-plate *b⁴*. I insert the portions of these tubes which project below the bottom of the box *b* in tubes, as *a* and *a^x*, 45 respectively, which I fit in the aforesaid holes formed in the bottom plate of the box *b*. These tubes, which are closed at their lower ends, are a little longer than the tubes they inclose, and their internal diameter is sufficiently large to leave a space around the tubes *d* and *d^x*. The result of this arrangement is that when the steam is admitted at

the inlet-pipe, which may be *e*, it fills the chamber *b²*, passes down the tubes *d*, and returns up on the outside of said tubes but inside the tubes *a^x* *a* into the chamber *b'*. It then descends the tubes and returns up through the tubes *d^x* to the chamber *b³*, from whence it passes to a pipe, which may be *g*, leading to the engine. The box and tubes, 55 as hereinbefore described, are fitted in the flue at the rear end of a boiler, as *c*, said tubes extending downward in the flue, so that the flames and hot gases from the furnace pass around said tubes in their passage 60 to the chimney, the steam passing through the superheater obtaining the full effect of the issuing heat by circulating through the tubes in a circuitous course more than once. By these means each particle of steam sweeps 65 an increased area of heating-surface at an increased velocity.

I do not confine myself to the precise number of tubes in each group as shown on the drawings or the number of groups in a series, 75 as these may be arranged according to the space in which said superheaters are intended to be placed, the boxes in which the tubes are fitted being correspondingly divided.

I claim as my invention—

An improved apparatus for superheating steam, comprising a box, a horizontal plate secured therein, dividing the box into upper and lower horizontal chambers, a vertical plate centrally dividing the upper chamber 85 in two, tubes each having a lower closed end and depending from the lower chamber, their upper open ends being in communication with said chamber, in combination with open-ended tubes within aforesaid tubes, each 90 open-ended tube terminating near the closed end of its surrounding tube, said open-ended tubes being secured in the horizontal plate at their upper ends and communicating, some with one division of the upper chamber, 95 and others with the other division, substantially as described.

In testimony whereof I have signed my name to this specification in the presence of two subscribing witnesses.

ANDREW BOLTON.
